UNITED STATES PATENT OFFICE.

J. ASHTON GREENE, OF BROOKLYN, NEW YORK.

DESIGN FOR A WRENCH.

SPECIFICATION forming part of Design No. 14,756, dated February 19, 1884.

Application filed July 2, 1883. Term of patent 14 years.

To all whom it may concern:

Be it known that I, J. ASHTON GREENE, of Brooklyn, in the county of Kings and State of New York, have invented a new and original 5 Design for Wrenches, which design is fully set forth in the following specification.

The design relates to diagonal wrenches such as described in Letters Patent of the United States No. 14,221, granted to Wm. Baxter, February 12, 1856; and its object is to 10 give to such wrenches a shape more graceful in outline and more convenient for handling.

A wrench design is shown in the accompanying drawings—in plan in Figure 1 and in 15 edge view in Fig. 2.

In the present design the edges of the tool are made curved or undulating—that is, their direction changes at every point. Near the middle, or the part where the screw is located, 20 the shank gradually widens, and toward each

end the edge behind the jaw, as well as that in front of it, curves outward, instead of continuing straight, or nearly so, to the end of the tool. The heads are given an ellipsoidal shape. In edge view, also, the shank gradually increases in thickness toward that point where the screw is located. 25

The new design imparts to the wrench a graceful and attractive appearance.

I claim—

The design for wrenches, substantially as herein described and shown.

In testimony whereof I have signed this specification in the presence of two subscribing witnesses.

J. ASHTON GREENE.

Witnesses:

GEO. C. PARKER,
E. A. BEHRINGER.
